UNITED STATES PATENT OFFICE.

HARRY G. MILLER, OF MILWAUKEE, WISCONSIN, ASSIGNOR TO MILLER SAW-TRIMMER COMPANY OF MICHIGAN, OF ALMA, MICHIGAN, A CORPORATION OF MICHIGAN.

METAL SAWING AND TRIMMING MACHINE.

985,828.

Specification of Letters Patent. Patented Mar. 7, 1911.

Application filed December 10, 1906. Serial No. 347,196.

To all whom it may concern:

Be it known that I, HARRY G. MILLER, a citizen of the United States, residing at Milwaukee, in the county of Milwaukee and State of Wisconsin, have invented new and useful Improvements in Metal Sawing and Trimming Machines, of which the following is a full, clear, concise, and exact description, reference being had to the accompanying drawing, forming a part of this specification.

The invention relates to improvements in apparatus for sawing and trimming metal stock and contemplates a novel construction and arrangement of parts in such apparatus whereby it is sufficiently adapted to saw and trim linotype slugs or the like without burring or finning; to trim cuts, make outside mortises, undercut plates, miter rule to any angle, make plate bevels for tacking or patent register hooks; split linotype slugs or trim off their ribs and shoulders to gain space, make leads and quads from old slugs, etc.

One of the objects of my invention is the provision of means in proximity to the work whereby accurate measurements for the operation on the material may be readily and quickly made.

Another object is the provision of readily adjustable means in proximity to the work for properly holding the material securely when it is operated on.

Various other objects will be brought out and made to appear in the following description of one form of apparatus worked out for practical purposes and embodying the invention.

With the above objects in view, my invention consists in certain novel features of construction and combination of parts, the nature of which will be readily understood from the following description taken in connection with the accompanying drawings.

In the drawings, like reference characters refer to like parts in the several views; of which;

Figure I is a plan view of apparatus embodying my invention; Fig. II is a plan view of the gage plate carrying the slideable straight-edge arm and gage mechanism for setting said arm accurately for an operation; Fig. III is a side elevation of the sliding table and parts thereon taken on the

line III—III of Fig. I; Fig. IV is a section taken on the line IV—IV of Fig. II; Fig. V is a section taken on the line V—V of Fig. II; Fig. VI is a section taken on the line VI—VI of Fig. II; Fig. VII is a detail of the toed member which is secured to the follower on the bracket of the slideable straight-edge arm; Fig. VIII is a section taken on the line VIII—VIII of Fig. III; Fig. IX is a section taken on the line IX—IX of Fig. III; Fig. X is a detail of the plunger pivoted to the end of the slide rod; Fig. XI is a section taken on the line XI—XI of Fig. X; Fig. XII is a section taken on the line XII—XII of Fig. X; Fig. XIII is a view of the micrometer gage and straight-edge arm adapted for long work; Fig. XIV is a view in detail of parts of the clamping mechanism. Figs. XV, XVI and XVII are detail views of the means for securing the clamping mechanism in position on the table.

As shown, a sliding table 2 is mounted in any approved manner on a stationary table 3, at one side of the saw 4 which is carried by a shaft journaled in bearings on a suitable pedestal or support. On the forepart of the sliding table 2 is mounted mechanism which is easily manipulated to obtain the proper positioning, relatively to the saw, of the stock or material to be operated on. The gage plate 5 has secured at its underside one or more followers 6 (Fig. III) which extend into an arc-form groove 7 in the top of the sliding table and thus constrains the plate to move from a position where the straight edge of the gage bar 8 is at right angles with the saw, to positions in which the same edge makes angles acute or obtuse with the saw. A locking pin 9 inserted through the gage plate into openings in the sliding table may be used to lock the gage plate in various positions on the sliding table and a set screw 10 is mounted on the gage plate to move in a slot 11 extending along the groove 7 in the sliding table 2, by which means the gage plate may be locked to the sliding table when it is moved to any angular position. An arm 12 having a straight edge in contact with the front or straight edge of the gage bar 8 and having a straight edge 13 at right angles to the gage bar is provided with a bracket 14 positioned immediately above the gage bar. The gage bar 8 is provided with a

toothed rack 15 adapted to fit the threads 16 of a worm revolubly mounted upon a spindle 17 journaled in suitable bearings 18 formed in the bracket on the arm 12. The 5 bracket 14 has secured thereto a follower 19 which fits over a longitudinal track 20 on the gage bar 8. The arrangement of the follower 19 on the bracket 14 provides a groove in the bracket in which the track 20 10 is adapted to fit. By this construction the weight of the outer end of the arm causes one wall of the groove to bear against the point 20^a on the track and the opposite wall of the groove to bear against the point 20^b 15 on the track, whereby a proper relation of the parts is maintained irrespective of the fit of the track 20 in the groove formed on the bracket. To one end of the follower 19 is secured the member 21 (Fig. VII) which 20 is provided with a toe 22 which fits a longitudinal recess in one of the walls of the groove 20. The toe of this follower fitting in the longitudinal groove prevents the bodily removal of the frame carrying the 25 worm from the gage part; at the same time, it permits the raising of the forward end of the frame which disengages the worm from the rack; therefore the worm 16 may with rapidity be moved to any position on 30 the gage bar by lifting the sliding arm to disengage the worm from the threaded rack and then moving the sliding arm to or near the desired position. At the top near the front edge, the gage bar is graduated to indicate picas, and there are preferably fifty 35 pica divisions to the left of the upstanding shoulder 23 (Fig. II) the gage being sufficiently longer to permit the micrometer gage to rest on the bar at the left of the 40 fiftieth division. Readings are taken at the right end of the bracket, it being noted that the width of the straight edge 13 equals that of the upstanding shoulder 23. A zone 24 at one extremity of the worm is graduated 45 and marked to indicate points; the entire circumference of the zone or the distance around the same being divided into twelve points or one pica. The teeth of the gage bar 8 which the worm engages and the 50 threads of the worm itself are so cut that their pitch bears a definite relation to the length of a point, and the worm is subdivided into graduations also having a definite relation to the length of a point. In 55 the present instance the pitch of the threads on the rack is such that a complete turn of the worm will move the bar 12 a distance equal to one pica, and a twelfth of a turn of the worm will move the bar a distance equal 60 to one point. This construction and arrangement permits of fine and accurate adjustment of the sliding arm whereby the length of the material sawed may be regulated to a point, or one-twelfth of a pica. 65 When it is desired to cut material of con-

siderable length, the attachment shown in Fig. XIII may be used. In this attachment a graduated slide rod 25 is attached to a member similar to the bracket of the sliding arm 12 and having similar parts associated 70 with the gage bar. The slide rod extends longitudinally of the main gage 8 on which it is slidably mounted, and carries the slideable arm 26 which is provided with a straight edge at right angles to the slide rod. 75 In this case, the rod is marked at points of 50 and 100 picas from the right end of the member on the main gage and thus the arm may be set to add these numbers of picas to any number of the picas, or picas and points, 80 indicated on the main and micrometer gages.

Another feature of my invention is the provision of means for holding the material in place upon the movable table as the latter is moved forwardly to bring the material to be acted on by the saw into operative relation therewith. In using sawing and trimming apparatus of this class particularly where the material or stock to be sawed consists of a considerable number of pieces, 85 as linotype slugs, it is important that these pieces shall be securely held in place and in proper position with each other and that they shall also be held tightly down upon the table. To meet these requirements the 90 pieces to be sawed should be pressed from the front and also from above, and my improvements provide means for effectively performing these functions.

Mounted on the sliding table 2 in suitable 100 proximity to its edge 27 is an upwardly projecting casing 28, which in position, canters toward the table forming an oblique angle with the plane thereof. The lower extremity of this casing is beveled to allow it to rest 105 flat upon the table when its body portion projects upwardly at an inclination as just explained. The casing 28 is provided with a depending pin or stem 29 whose axis extends at right angles to the plane of the 110 table. This stem 29 enters a circular recess formed in the sliding table 2 and a small round bar 30 is secured in position in the recess in the rear.

The casing 28 is provided with a stem 29 115 which is formed integrally on a plug 31 held in the bottom of the casing by a pin or key 32, making the casing and plug substantially integral, so far as the operation is concerned. This stem 29 has formed 120 therein a transverse groove 33 and has one side flattened as at 33^a. In attaching the work-holding device to the table the device is swung at an angle to the right about 90 degrees from the position shown in the drawings and the stem 29 is inserted in the circular recess or opening formed in the table to receive the same, the flattened portion 33^a of the stem permitting the stem to pass the pin 30. When the work-holding device is 125 130

swung into normal position the groove 33 will engage the pin 30 and the work-holding device will be held in position on the table. In removing the work-holding device from the table it is swung to the right about 90 degrees or until the flattened or straight edge portion 33^a is opposite the pin 33, when, it will be seen, the stem 29 may be readily disengaged from the pin 33.

10 Above the plug 31 in the casing 28 is located a movable piston 34, which fits closely within the casing and is connected with a piston rod 35 surrounded by a coiled spring 36, one extremity of which spring acts on the piston 34 while the other extremity engages the upper end of the casing. The piston rod 35 extends upwardly through an opening in the top of the casing and has its upper portion bifurcated to form two arms 37, adapted to receive one extremity of a slide 38 provided with an opening to receive the pin 39, passed through registering apertures formed in the parts 37 and the rear extremity of the slide arm 38. This 20 arm 38 consists of a bar which extends forwardly from the casing 28 and has slidably mounted thereon the retaining device 40, consisting of the upper member 41 provided with a groove fitting the top of the arm 38, and the lower grooved member 42, which is pivoted at 43, to the upper member and provided with a depending projection or jaw 44. At the forward extremity of the upper member is provided a part 45 with 30 an opening through which the arm may pass and a handle 46 for shifting the device along the arm 38. At the rear at 47, the groove in the lower member is deeper and slopes downwardly. The lower edge of the member 42 is provided with a strip 48 of suitable yielding material, as rubber, whereby stock or material to be operated on is not injured by downward pressure of the device.

With the above construction in shifting 45 the retaining device the lower member falls away from the slide rods so that the whole may be moved on the rod with a minimum of frictional resistance.

Conveniently mounted pivotally on the 50 gage bar 8 is a spring operated latch 49, provided with an arm 50, arranged to engage the retaining device after the same has been brought into operative relation with respect to the material to be operated on, to thereby hold that device down on the material.

In order to hold material which it is desired to split or trim longitudinally, I provide clamping means which may be readily attached to the straight edge of the arm 12. 60 On the side at the front of the straight edge a small plate 51 having a counter-sunk opening 52 therethrough, below its center and its serrated front edge 53 fits on the eccentric head 54 of a small shaft 55 which journals 65 in the boss 56 on the arm 12. One end of

the material to be operated on is pressed against the serrated edge of the plate 51, and then the member 57 slidably mounted on the straight edge is moved and pressed tightly against the other end of the material and set by means of the screw 58. The material may be instantly released from the clamping means by raising a lever which may be inserted into the opening 60 in one end of the shaft 55, to thereby rotate the shaft and cause its eccentric head to turn in the opening in the plate, which will move the plate upwardly and forwardly away from the end of the material.

From the foregoing description it is believed that the use and operation of my improved apparatus will be readily understood. If it is assumed that the material is to be cut to a length designated by a certain number of picas and points, the arm 12 is first raised to disengage the worm of the micrometer from the teeth of the main gage bar after which the arm 12 is quickly moved to a position where the distance between the straight edge and the saw will be the given 80 number of picas. The worm is then thrown into engagement with the teeth of the bar taking care that the zero mark on the zone 24 is opposite the adjacent zero mark on the journal bearing of the worm. The worm is 85 then turned until its degree of revolution is indicated by a number of points equal to the number of points to be added to the measurement expressed in picas. The operator will then know that the distance between 90 the straight edge of the arm and the saw will be that required to reduce the material to the length desired.

While the stock or material to be sawed is being placed on the table the arm 38 with 105 the retaining device thereon may be thrown to the left toward the rear end of the table, the arm 38 turning on the pin 39 if desired. As soon as the stock is in place the slide arm and the retaining device 40 will be moved 110 forwardly and thrown to the position shown in Fig. 1 of the drawing. The retaining device is moved forwardly by grasping the handle, until the jaw engages the rear end of the material or stock. The user of the device then presses down upon the forward 115 extremity of the retaining device and if desired locks it in this position by means of the latch, whereby the stock is held securely in place both from above and from the rear. 120 The object of giving the casing an inclined position or a position inclined forwardly from its base is to cause the arm 38 to move forwardly and upwardly simultaneously as the piston 34 moves upwardly against its 125 spring in response to the downward pressure of the retaining device on the material. It is evident that if the material projects somewhat above the gage bar 8 there will be a tendency to raise the piston 34 in its casing 130

against the coiled spring 35. If this casing 28 occupied a vertical position or a position at right angles to the plane of the table the material would act as a fulcrum for the slide 5 arm 38, and the latter in turning on its fulcrum would have a tendency to throw the jaw on the lower member of the retaining device rearwardly and upwardly, since the movement would be from the fulcrum point 10 as a center. This movement would leave a space between the lower forward extremity of the jaw 44 and the material which it should closely engage, and this space would diminish from the lower part of the jaw upwardly. In order to prevent this result, the casing 28 has been inclined forwardly from 15 the table, whereby as the piston 34 moves upwardly, as occasion may require, the jaw, while being moved upwardly, also moves 20 forwardly at the same time, thus keeping it in close contact with the rear end of the material. In this way the material is held tightly in place against the gage bar, regardless of the upward movement of the jaw 25 or its movement above the plane of the table, since the devices are so constructed and arranged that the resultant of the upward and forward movement of the arm 38 and the retaining device thereon is to give the 30 forward face of the jaw a vertical movement or a movement perpendicular to the table.

While I have herein described one form in which I have worked out my invention 35 for practical purposes, I do not desire to be limited to exact details of construction shown and described, since many changes in the details of construction and arrangement, and combination of parts, as set forth, will 40 occur to a person skilled in the art and are intended to fall within the purview of the claims appended hereto.

Having thus described my invention, what I claim as new and desire to secure by Letters 45 Patent, is:

1. In a device of the class described, the combination with a table, of an inclined casing extending upwardly therefrom, a spring-held piston located in said casing, a 50 rod connected with the piston, an arm pivotally connected with the upper extremity of the rod, a retaining device slidably arranged on the arm, said retaining device having a depending jaw adapted to engage material 55 or stock on the table from the rear, while its portion in front of the jaw engages it from above.

2. In a device of the class described, the combination with a table and a gage bar 60 mounted thereon, of a casing mounted on the table and occupying an inclined position, a piston located in said casing, the latter being connected with the table in the rear of the bar, a rod connected with the piston 65 and extending through an opening formed

in the top of the casing, a spring located within the casing and engaging the piston from above, an arm pivotally connected with the said rod and a retaining device on said arm provided with a depending jaw adapted 70 to engage stock on the table from the rear, while the gage bar engages it in the front.

3. In a device of the class described, the combination with a table, of an inclined 75 casing whose lower extremity is cut to conform to the plane of the table, the lower extremity of the casing having a vertical depending part engageable with the rod in a recess formed in the table, and adapted to turn therein, a spring-held piston located in 80 the casing and provided with a protruding rod, an arm connected with said rod, and a part slidably mounted on the arm and having a depending jaw or part adapted to engage material or stock on the table.

4. The combination with a table, of a casing mounted on the table and inclined to the plane thereof, the casing being provided with a vertical depending part occupying a 90 recess formed in the table and adapted to turn therein, a spring-held piston located in the casing and provided with a rod protruding from its upper extremity, an arm pivotally connected with the upper extremity of the rod, and a holding member slidably mounted on the arm and provided with a depending jaw, a yielding lower surface extending forwardly of the rod, and a manipulating handle, substantially as described.

5. The combination with a table, or other suitable support, of an arm carrying a retaining device, and means for causing said arm and said retaining device to move forwardly and for causing the front end of 105 said arm to move upwardly when said arm and the retaining device are operated.

6. The combination with a table or other suitable support, of an arm hinged or pivotally connected with the table, and a slidable 110 work holding device on the arm, said device being provided with a depending jaw, and constructed to be frictionally held in position.

7. The combination with a table or other suitable support, of an arm hinged or pivotally connected with the table, a retaining device provided with grooves fitting the upper and lower portions of the arm, the groove fitting the lower portion of the arm sloping downwardly to the rear of the device.

8. The combination with a cutting device, of feeding means associated therewith, a gage associated with said feeding means having one member thereof movable, and 125 means for locking the material to be cut to said movable member.

9. The combination with a rotary cutting tool, of feeding means associated therewith, a gage associated with said feeding means 130

having one member thereof movable and means for locking the material to be cut to said movable member.

10. The combination with a rotary cutting tool, of a gage movable relatively thereto, and having one member thereof adjustable and means for locking the material to be cut to said adjustable member.

11. The combination with a rotary cutting tool, of a gage movable relatively thereto, and having one member adjustable, work holding clamps on said movable member and means for moving one of said clamps relatively to the other to grip the work between them.

12. The combination with a rotary cutting tool, of a gage movable relatively thereto and having an adjustable member, work holding clamps on said adjustable member, one of said clamps being adjustable on the gage member and the other relatively movable to grip the work between them.

13. The combination with a rotary cutting tool, of a gage movable relatively thereto and having one of its members adjustable, work holding clamps on said adjustable member and a cam for moving one of said clamps.

14. The combination with a rib track, of an arm slideable thereon and having a slot substantially in one end thereof, to receive the rib, the weight of the arm causing the wall of the slot on one side to engage the side of the rib at a point above its vertical center and the wall of the slot on the opposite side to engage the rib at a point below its vertical center, whereby the arm is maintained in a positive relative position with respect to the track irrespective of the fit of the track in the slot.

15. The combination with a stationary member, of a movable member slideable thereon and supported adjacent one end, one of said members having a rib and the other having a slot to receive the same, the weight of the outer end of the movable member causing the wall of the slot on one side to engage the side of the rib at a point above its vertical center and the wall of the slot on the other side to engage the rib at a point below its vertical center whereby the movable member is maintained in a positive relative position with respect to the stationary member irrespective of the fit of the rib and the slot.

16. In a device of the character described, the combination with a stationary member, of a movable member slideable thereon, and supported adjacent one of its ends, one of said members having a rib and the other a slot to receive the same, the weight of the outer end of the movable member causing the contact surfaces of the two members to be deflected from parallelism to cause said contact surfaces to bind at two or more

points, whereby lost motion is eliminated and the movable member is maintained in a positive relative position with respect to the stationary member irrespective of the fit between the rib and the slot.

17. In a device of the character described, the combination with a stationary member, of a movable member slideable thereon, said movable member being supported by a hook-shaped flange adjacent one end extending over the other member, the weight of the outer end of the movable member causing the contact surfaces of the two members to be deflected from transverse parallelism to cause the same to bind at two or more points whereby lost motion is eliminated and the movable member is maintained in a positive relative position with respect to the stationary member irrespective of the fit between the contact surfaces.

18. In a device of the character described, the combination with a stationary member, of a movable member slideable thereon, and supported adjacent one of its ends, one of said members having a rib and the other a slot to receive the same, the contact surfaces of the two members being deflected from transverse parallelism to cause the same to bind at two or more points whereby lost motion is eliminated and the movable member is maintained in a positive relative position with respect to the stationary member irrespective of the fit between the contact surfaces.

19. In a device of the character described, the combination with a stationary member, of a movable member slideable thereon, said movable member being supported by a hook-shaped flange adjacent one end extending over the other member, the contact surfaces of the two members being deflected from transverse parallelism to cause the same to bind at two or more points whereby lost motion is eliminated and the movable member is maintained in a positive relative position with respect to the stationary member irrespective of the fit between the contact surfaces.

20. In a device of the character described, the combination with a stationary member, of a movable member detachably mounted thereon and supported adjacent one of its ends, one of said members having a rib and the other a slot to receive the same, the weight of the outer end of the movable member causing the contact surfaces of the two members to be deflected from transverse parallelism to cause the same to bind at two or more points whereby lost motion is eliminated and the movable member is maintained in a positive relative position with respect to the stationary member, irrespective of the fit between the rib and the slot.

21. In a device of the character described, the combination with a stationary member,

of a movable member detachably mounted thereon, said movable member being supported by a hook-shaped flange adjacent one end extending over the other member, the 5 weight of the outer end of the movable member causing the contact surfaces of the two members to be deflected from transverse parallelism to cause the same to bind at two or more points whereby lost motion is eliminated and the movable member is maintained in positive relative position with respect to the stationary member irrespective of the fit between the contact surfaces.

22. In a device of the character described, 15 the combination with a stationary member, of a movable member detachably mounted thereon and supported adjacent one of its ends, one of said members having a rib and the other a slot to receive the same, the contact surfaces of the two members being deflected from transverse parallelism to cause the same to bind at two or more points whereby lost motion is eliminated and the movable member is maintained in a positive relative position with respect to the stationary member irrespective of the fit between the rib and the slot.

23. In a device of the character described, 30 the combination with a stationary member, of a movable member detachably mounted thereon, said movable member being supported by a hook-shaped flange adjacent one end extending over the other member, the contact surfaces of said members being deflected from transverse parallelism, so as to cause the same to bind at two or more points whereby lost motion is eliminated and the movable member is maintained in positive relative position with respect to the stationary member irrespective of the fit between the contact surfaces.

24. In a device of the character described, 45 the combination with a rotary cutting tool, of a sliding table, a gage device mounted on said table, comprising a relatively stationary member extending at an angle to the line of cut of the tool, and an adjustable member extending substantially at right angles to the stationary member, said relatively stationary member being pivoted to be moved in the arc of a circle, having its center on the line of cut of the cutting tool.

25. In a device of the character described, 55 of a work supporting table, a gage mounted on said table and movable relatively to said tool, comprising a relatively stationary member extending at an angle to the line of cut of the tool and an adjustable member extending 60 at substantially right angles to the stationary member, said relatively stationary member being pivoted to be moved in the arc of a circle having its center on the line of cut of the cutting tool.

65 26. In a device of the character described,

the combination with a rotary cutting tool, of a sliding table, a gage mounted on said table, comprising a relatively stationary member extending at an angle to the line of cut of the tool and an adjustable member 70 extending at substantially right angles to the stationary member, said stationary member being pivoted to move in the arc of a circle having its center on the line of cut of the cutting tool and a work holding 75 vise for locking the material to be cut in said gage.

27. In a device of the character described, 80 the combination with a rotary cutting tool, of a work supporting table, a gage device mounted on said table, movable relatively to said cutting tool and comprising a relatively stationary member extending at an angle to the line of cut of the tool and an adjustable member extending at substantially right angles to the stationary member, 85 said relatively stationary member being pivoted to be moved in the arc of a circle having its center on the line of cut of the tool and a work holding vise extending substantially parallel with the cutting tool for holding the work in said gage.

28. In a device of the character described, 90 the combination with a relatively stationary member having a screw rack on one face 95 thereof and a slot, of a movable member extending substantially at right angles to said stationary member and having a rib adjacent one end arranged to fit in said slot and a screw carried by said movable member arranged to engage said rack.

29. In a device of the character described, 100 the combination with a stationary member, of a movable member slidable thereon and supported adjacent one of its ends, one of said members having a screw and the other a rack adapted to coöperate therewith, one of said members having a rib and the other a slot to receive the same, the weight of the outer end of the movable member 105 causing the contact surfaces of the two members to be deflected from parallelism causing said contact surfaces to bind at two or more points whereby lost motion is eliminated and the movable member is maintained in positive relative position with respect to the stationary member irrespective of the fit between the rib and the slot.

30. In a device of the character described, 110 the combination with a stationary member having threads formed on one face, of a movable member slidable thereon, said movable member being supported by a hook-shaped flange adjacent one end and extending over the other member, a screw carried 115 by said hook-shaped flange arranged to engage said threads, the weight of the outer end of the movable member causing the contact surfaces of the two members to be deflected from transverse parallelism to cause 120 125 130

the same to bind at two or more points whereby lost motion is eliminated and the movable member is maintained in a positive relative position with respect to the stationary member irrespective of the fit between the contact surfaces.

31. In a device of the character described, the combination with a cutting tool of a gage for positioning the work with respect to 10 said tool, a table for supporting the work, and a vise for locking the work in said gage

comprising a supporting member detachably mounted on said table, and a movable member slidably connected therewith for engaging the work.

In witness whereof, I have hereunto subscribed my name in the presence of two witnesses.

HARRY G. MILLER.
